WITNESS: G. J. Evans

UNITED STATES PATENT OFFICE.

ELMORE HAY HARRINGTON, OF NEW SMYRNA, FLORIDA.

TOBACCO STICK.

Application filed July 31, 1925. Serial No. 47,313.

This invention relates to tobacco sticks and has for an object the provision of a strong and durable stick provided with means to permit of the tobacco being quickly and securely attached thereto and quickly and easily removed therefrom and thus provide a stick which will last for an indefinite period in addition to cheapening the cost of tobacco curing while reducing the time required for handling the tobacco.

Another object of the invention is the provision of a stick which, in addition to the above advantages, may be made from relatively light angle iron and thus decrease the weight of the stick and increase its durability and at the same time decrease cost of manufacture.

With the above and other objects in view, the invention further includes the following novel features and details of construction, to be hereinafter more fully described, illustrated in the accompanying drawings and pointed out in the appended claims.

In the drawings:—

Figure 1 is a perspective view of a tobacco stick constructed in accordance with the invention.

Figure 2 is an enlarged fragmentary longitudinal sectional view of the same.

Figure 3 is a fragmentary edge view.

Figures 4 and 5 are enlarged sections taken respectively on the lines 4—4 and 5—5 of Figure 2.

Referring to the drawings in detail where-in like characters of reference denote corresponding parts, the stick as shown is made from a pair of transversely channel shaped members 10 which are secured together by suitable fastening devices as indicated at 11 so as to provide spaced gripping edges 12 which extend longitudinally upon opposite sides of the stick and which are preferably toothed or serrated as shown at 13. The ends of the channel are closed by end members 14 whose outer edges are preferably rolled.

Extending longitudinally upon opposite sides of the stick between the gripping edges 12 are retaining wires 15. The opposite ends of these wires extend through openings 16 provided in oppositely extending guide plates 17 which are secured within and extend outwardly from the angle members 10. Intermediate guide members 18 are located substantially central of the length of the stick upon opposite sides thereof

and these guide members 18 are provided with notches 19 to receive the retaining wires 15, yet permit of the wires being moved outward as shown by the dotted lines in Figure 2 of the drawings. A spring 20 which extends transversely through the stick between the intermediate guide members 18 has its opposite ends connected to the retaining wires 15 and acts to yieldingly hold these wires within the notches 19. The opposite ends of the wires 15 are connected to the opposite ends of coiled springs 21, one of these springs extending through an opening 22 provided at each end of the stick to tension the wires 15.

It will be apparent from the foregoing description and accompanying drawings, that the invention provides a relatively light, strong and durable tobacco stick having means for clamping the tobacco between the gripping edges 12 and the retaining wires 15 so that the tobacco will be securely held in place, the securing means being of a character to permit of the tobacco being readily attached to or removed from the stick.

The invention is susceptible of various changes in its form, proportions and minor details of construction and the right is herein reserved to make such changes as properly fall within the scope of the appended claims.

Having described the invention what is claimed is:—

1. A tobacco stick comprising a pair of channel shaped members secured together to provide spaced gripping edges upon opposite sides of the stick, a retaining wire extending longitudinally upon each side of the stick between the gripping edges and means to yieldingly hold the retaining wire in retaining position.

2. A tobacco stick comprising a pair of channel shaped members secured together to provide spaced gripping edges upon opposite sides of the stick, a retaining wire extending longitudinally upon each side of the stick between the gripping edges, outwardly and oppositely extending guides at each end of the stick to slidably receive the wire and position the latter slightly beyond said gripping edges and means to yieldingly hold the wire in retaining position.

3. A tobacco stick comprising a pair of channel-shaped members secured together to provide oppositely disposed longitudinally

extending recesses and gripping edges along the side edges of the recesses, a retaining wire extending longitudinally along each side of the stick; means to yieldingly hold the retaining wire in position and plates disposed within the recesses and extending beyond said gripping edges and having wire receiving openings therein to guide and position the wire slightly beyond said gripping edges.

4. A tobacco stick comprising a pair of channel-shaped members secured together to provide oppositely disposed longitudinally extending recesses and gripping edges along the side edges of the recesses, serrations throughout the length of the gripping edges, a retaining wire extending longitudi-

nally along each side of the stick and cooperating with the gripping edges to engage the tobacco, means to yieldingly hold the retaining wire in position and means to guide and position the retaining wire slightly beyond the gripping edges.

5. A tobacco stick comprising a pair of channel-shaped members secured together to provide spaced gripping edges upon opposite sides of the stick, a retaining wire extending longitudinally upon each side of the stick between the gripping edges, springs connecting the ends of the wires and springs connecting the wires intermediate the ends of said wires to yieldingly hold the latter in retaining position.

ELMORE HAY HARRINGTON.
